US00D469878S

(12) **United States Design Patent** (10) Patent No.: **US D469,878 S**
 Davis et al. (45) Date of Patent: ** Feb. 4, 2003

(54) **MULTIPURPOSE WRAP**

- (75) Inventors: **Leane Kristine Davis**, Milford, OH (US); **Nancy Jean McCarthy**, Cincinnati, OH (US)
- (73) Assignee: **The Procter & Gamble Company**, Cincinnati, OH (US)

(**) Term: **14 Years**(21) Appl. No.: **29/129,621**(22) Filed: **Sep. 19, 2000****Related U.S. Application Data**

- (62) Division of application No. 29/110,621, filed on Sep. 15, 1999, now Pat. No. Des. 435,910.
- (51) **LOC (7) Cl.** **24-04**
- (52) **U.S. Cl.** **D24/206; D24/190; D24/189**
- (58) **Field of Search** D24/206, 190, D24/189, 200; D2/500, 600; 2/1, 171, 257, 279; 607/1, 96, 108-111

(57) **CLAIM**

The ornamental design for a multipurpose wrap, as shown and described.

DESCRIPTION

FIG. 1 is a front view of a multipurpose wrap, embodying our new design;

FIG. 2 is a side elevational view thereof; the opposite side elevational view thereof being a mirror image;

FIG. 3 is a back view thereof; and,

FIG. 4 is a bottom view thereof; the top view thereof being a mirror image.
